UNITED STATES PATENT OFFICE.

ELISHA C. SLOAN, OF BOSTON, MASSACHUSETTS, ASSIGNOR TO THE CHADWICK LEAD WORKS, OF SAME PLACE.

APPARATUS FOR INCASING WIRES WITH LEAD.

SPECIFICATION forming part of Letters Patent No. 355,844, dated January 11, 1887.

Application filed March 15, 1886. Serial No. 195,299. (No model.)

To all whom it may concern:

Be it known that I, ELISHA C. SLOAN, of Boston, in the county of Suffolk and State of Massachusetts, a citizen of the United States, 5 have invented a new and useful Apparatus and Method of Using the same for Incasing Wires with Lead or other Soft Metal, of which the following is a full, clear, and exact description, reference being had to the accompanying drawings, forming a part of this specification, in explaining its nature.

A great necessity of the time is to place in the large cities telegraph-wires under ground, and in order to protect the conducting-wire 15 from contact with the ground it is usually enveloped in some non-conducting material which insulates it; and in order to protect the insulation from the destructive action of earth-contact with it, it has lately been customary to 20 cover such insulated wires with some soft and poor conducting metal—such, for instance, as lead—and this lead covering for insulated wires is also desirable for wires that are to be embedded in plastering for electrical service 25 in buildings; and besides this other electrical conductors are being experimented with in which a lead envelope is applied to serve a different electrical purpose. Consequently at the present day the covering of wires or 30 groups of wires by a lead envelope, and perhaps, also, by a tin or other metal envelope, is an important thing to be accomplished readily, cheaply, and certainly, and the present invention is intended for the application 35 of such metals as can be put on in the pipe-press for which "lead" is used as a generic name. Of course it is desirable that this protecting surface of lead should be as thinly applied as possible, in order that the expense of 40 useless metal may not be incurred by having it too thick in one place, nor insufficient protection be given by having it too thin in other places.

It has also been found in applying lead to 45 electric conductors that if the conductor is exposed too long to heat the insulation is apt to be disturbed, and in some instances destroyed; and if oil or other liquid is employed to preserve the conductor from injury by heat while 50 coating with lead, this introduces another source of injury to the insulation of the con-

ductor. It is with a view of applying lead or tin in the lead-pipe press to electrical conductors that the present apparatus is devised, whereby it is not necessary to expose the insulated wire for any great length of time to heat, or to carry it through a heated place for any great distance, and in which, also, it is not necessary or admissible that any cooling liquid should be applied to the insulated wire 55 or the metallic envelope after that has been put upon the wire. The apparatus also serves an admirable purpose in gaging the thickness of the metallic envelope.

In the drawings, Figure 1 is an elevation of 65 the machine which I employ. Fig. 2 is a vertical section through the die-holder and its dies in the place where the adjusting-screws are situated. Fig. 3 is an enlarged view of a part of a die-holder and its dies. Fig. 4 is an elevation 70 upon the same scale as Fig. 2 of the die-block. Fig. 5 is an elevation of the die which shapes the interior of the lead casing called the "core" or "coring-die." Fig. 6 is an elevation of the die which shapes the exterior of the lead casing. Fig. 7 is a view of the scale attachment 75 to the adjusting-screws F F'.

In Fig. 1, A is the motor which furnishes power to force the metallic lead into its proper place upon the wires. By means of the yoke 80 a, which is attached by connecting-rods a' a' to another yoke, a'', the piston B, which piston is attached to the yoke a'', is held stationary, and the cylinder C, containing the lead or tin, is forced up against it. This cylinder C is 85 like the ordinary cylinder of a lead-press, and the motor A is supported upon a base or on the top of a column in an ordinary way.

Turning now to Fig. 2, the cylinder C is represented with its contents of lead or other metal 90 suitable for this operation at c. Its bottom is made with a disk-yoke, c', which is connected by holding-down bolts d with the flanged top D of the hydraulic piston. In the interval between these two yokes, and forming the bottom of the hollow part of the cylinder C, is placed a die-block, E, which is made in two parts, as shown in Fig. 4, one of which is marked E and the other E', and this die-block is centered and held in place by the securing-block F', in which are made two opposite threaded cavities for the adjusting-screws F F', 95 100

which adjusting-screws have hollow axes. The upper part, E, of the die-block is formed with a gabled roof next the hollow part of the cylinder C, and at the lower part of the incline on each side of the ridge of this roof is a channel, e. The lower side of the upper part of the die-block E is made with crossing semi-circular recesses, one opposite pair of which semicircular recesses communicate with the channel e, and the other opposite pair, f, form the recess for the dies which regulate the application of the lead covering. The lower part, E', of this die-block is formed with a neck, as shown in Fig. 2, which fits into an appropriate cavity in the securing-block F', and the upper part of it is formed with crossing semi-cylindrical recesses e' f', the die-block being adjusted in place in the securing-block with its recesses e' in connection with the channels e, and with its recesses f' opposite the place of the adjusting-screws F F².

It will be seen that there is a passage for the lead or other metal to the cavity in which the dies are to fit. These dies are two in number, one of which, g, forms and gages the outside of the lead covering, and the other of which, h, forms and gages the inside of the lead covering. I prefer to make these dies in two parts, as shown in Fig. 2, one of which would be a die-holder, to which the letter G or H is applied in the drawings, and the other of which would be the die proper, which is represented in Figs. 5 and 6; but it is obvious that the die-holder and die proper might be readily made in one piece, if desired. It is better, however, to have them, as described, in two pieces, because of more ready adjustment of the machine and requiring fewer large parts. These dies g and h can be set up toward each other by the screws F F², and can be put in any situation that is desirable in order to apply the lead covering, which situation will require to be changed according to the thickness of the envelope, the quality of metal, and various other conditions of the work.

I have marked in the drawings what I have heretofore called the "die proper," Fig. 3, g and h. The die g has a concave tapered cavity presented toward the lead, and the die h has a projecting conical point which approaches the internal cone of the die g. A wire, i, being passed through the hollow screw F, the die-holder H and its die h, and the die g and its die-holder G, and through the hollow screw F², is in a condition to be covered with lead. The lead in the cylinder, being pressed by the piston B, flows through the channels e into the transverse channels e', with which these channels e communicate, and hence sidewise into a considerable cavity in the center of the die-block E E', which surrounds the dies h g.

For the purposes of this description it is now desirable to distinguish between the two dies g and h, and for the purpose of distinguishing between them in the remaining part of this specification, the die h, having a conical point, will be called the "coring-die," and the

die g will be called the "outside die." By moving the coring-die h by the screw F toward or from the outside die, g, an adjustment can be made of the thickness and tightness with which the lead is applied to the wire within certain limits desirable in practice, and by moving the outside die, g, toward or from the coring-die h an adjustment can be made of the thickness and tightness of the metal applied, the mobility of both dies apparently giving more control over these qualities than a single adjustment, so that by this arrangement of having both coring-die h and the outside die, g, adjustable toward and from each other not only the outside diameter of the lead covering, but also the inside diameter of the lead covering, can be gaged within certain practical limits. This is desirable, because in some sorts of insulation the tightness or looseness of the envelope modifies the insulation, and it is also desirable because with some sorts of insulation the closeness or remoteness of the lead envelope modifies the conducting power of the wire, which is explained by electricians as a disturbance or alteration caused by the so-called "magnetic field."

Let us suppose now that the dies are in place and the wire passed through them, and an order has been given to produce a lead covering laid on with a certain degree of tightness and a certain weight to the foot. Pressure is applied to the lead and a short piece of wire allowed to run through. This is weighed and the tightness of it examined, and if laid on too tight the adjusting-screw F is set up a little. If the weight of the covering is correct, the adjusting-screw F² would be adjusted a compensating amount; but if the weight of the covering was too much or too little the adjusting-screw F² would be set up a little less or a little more, and after having found by experiments and stripping a few feet of the wire that the tightness is right and the weight of the covering is right, the machine can be run continuously and new lead supplied from time to time, which will unite in the usual way under pressure with thick coverings or at any rate under heat and pressure with the remainder of the old lead until any desired quantity of wire is covered practically of uniform weight and uniform tightness. Scales f², Fig. 7, showing the position of the dies, are attached to the heads of screws F F², which enable any adjustment to be repeated without experiment.

It will be seen that the wire is constantly exposed to air until it actually enters the coring-die h, where it is for only a short distance exposed to the heat of the lead, and immediately after passing through the outside die, g, it again comes into a cavity where the air circulates, and presently into the open air, wherein it will rapidly cool.

It will be noticed that the conical end of the coring-die h is much blunter and at a much greater angle with the axis of its cone than has been usual in the cores of lead-pipe ma-

chines or machines for covering wires with lead, and this prevents it from springing out of its place, and also gives with a very moderate motion to and from the hollow of the die 5 *g* a very considerable change in the tension of the metal, and I believe this bluntness of the conical end of the die is to a considerable extent the reason why the tension is so readily adjusted; and hence in speaking of the coring-die *h* in the claims I do not intend to claim a coring-die which has a long and fine conical point, but only one which has a blunt conical point substantially like the one shown herein—namely, a point which presents at the crossing of the two sides extended an angle of forty-five degrees at least, and I prefer that this angle at the apex of the cone should be approximately near to a right angle.

I am aware that various apparatus for running wire to be covered transversely of the motion of the main column of the lead in the cylinder have been described and patented, but the peculiar combinations of this apparatus wherein its efficiency consists have not 20 been hitherto announced. The adjustment described is such that it is possible to put on the lead with almost no compression upon the wire, and also to put it on with a less diameter outside than that of the interior cylindrical part of the outside die, *g*, and apparently the lead is rolled onto the wire very much as a stocking is rolled onto the leg.

As the outside die is not fitted in laying on the lead by this machine, the imperfections of 35 the cable or wire are shown on the outside of the lead covering, which is an advantage in laying the covered wire, as an imperfect piece may be detected and cut out before it is laid. This method of rolling on the lead also allows it 40 to be put on very evenly and exactly. Thus less weight of lead gives as great protection as a greater weight applied unevenly.

The change from one size of die to another or from wire covering to other lead work can 45 be very readily made in this machine, more so than in any other which I have ever used.

Having thus fully described my invention, I claim and desire to secure by Letters Patent of the United States—

50 1. The combination, with a lead-cylinder and its piston, of a die-block, *E E'*, forming

the bottom of the hollow part of the cylinder, and held in place by suitable means, said die-block being provided with the vertical channels *e* and transverse channels *e' f f'*, substantially as and for the purposes described. 55

2. In combination with the die-block *E E'*, provided with vertical and horizontal channels, as described, the conical-ended coring-die *H h* and the outside die, *G g*, arranged 60 transverse to the cylinder *C*, substantially as described.

3. In combination with the die-block *E E'* and its dies *g h*, the adjusting-screws *F F'*, substantially as described. 65

4. The combination of the adjusting-block *F'* with the die-block *E E'*, the dies *g h*, and the hollow adjusting-screws *F' F*, substantially as described.

5. The combination, with an outside die, *g*, 70 of an adjusting-screw, *F'*, as a means for gagging the size of the exterior of the lead cover for wire independent of the interior cylindrical diameter of said die, substantially as described. 75

6. The combination of the die-holder *H* and its die *h* with and arranged in the die-block *E E'*, and in combination with the adjusting-screw *F*, whereby the coring-die *h* is adjusted to and from the outside die, *g*, without opportunity to spring or get out of center, substantially as described. 80

7. The combination, with one of the dies for the formation of a metallic tube and with the adjusting-screw thereof, of a scale-head, *f'*, 85 applied to the exterior end of said adjusting-screw, whereby the position of the forming-die within the machine and in contact with the metal to be run may be registered upon the outside of the machine, substantially as described. 90

8. The construction of the coring-die *h* with a point the sides of which if prolonged would intersect at an angle greater than forty-five degrees and proximately near a right angle, substantially as described, and for the purpose stated. 95
